UNITED STATES PATENT OFFICE

ALEXANDER NYMAN, OF NEW YORK, N. Y., ASSIGNOR TO DUBILIER CONDENSER CORPORATION, OF NEW YORK, N. Y., A CORPORATION OF DELAWARE

ELECTRIC TERMINAL

Application filed September 10, 1925. Serial No. 55,594.

This invention relates to improvements in electrical terminals of the high tension type and particularly to a type of terminal adapted for leading high tension, high frequency currents into electrostatic condensers and other electrical apparatus.

With high tension leading-in terminals now in use, owing to the losses that occur due to the action of the high frequency currents upon the insulating media which are necessary for the support and maintenance of the terminal, considerable heat, frequently of a destructive character, is generated. The limitation or avoidance of such losses is one of the advantages of my improved terminal.

Another object of my invention is to provide a type of terminal which is substantially constructed and at the same time embodies protective insulating surfaces of relatively large extent.

A further object of my invention is the provision within the terminal of a long sparking or safety gap which is an indispensable feature in the operation of a terminal of this sort.

I prefer mica as the insulation for my terminal, but other dielectrics of similar properties may be used. Mica has proven to be the best material for my purpose, although mica can be procured only in flat sheets and must therefore be employed in sheet form.

As experience shows that when an electric flux enters or leaves the surface of a flat dielectric more or less perpendicularly to that surface, losses will occur; while if the dielectric flux is made to pass substantially parallel to the flat surface, the insulation is better and the resultant losses, the least; so in the construction of my improved terminal, I employ a flat disc or discs of mica, the plane of which extends in approximately the same direction as the electrostatic lines of force between surfaces or parts of my terminal, having a difference of electric potential.

The invention will be more fully explained by reference to the accompanying drawings which illustrate an embodiment thereof.

Figure 1 is a vertical section of a terminal according to my invention;

Figure 2 is a top view of the same; and

Figure 3 is a diagram of the electrostatic field existing between an electrode and a casing or support therefor in my terminal.

The same numerals identify the same parts throughout.

A centrally located, round conductor rod is indicated at 1. This rod is threaded on its ends and is encircled by a sleeve 2 for a short distance adjacent the middle, to present the shoulders 3 on the rod 1. Abutting these shoulders 3 are the perforated discs or diaphragms 4 and 5 of mica. The clamping means or nuts 6 and 7 on the threaded portions of the rod 1, press the stacks of mica washers 8 and 9 against the disks 4 and 5 to retain the mica discs 4 and 5 firmly in position. The edges of the nuts 6 and 7 are rounded for a reason that will appear later.

Encircling the rod 1 is a metallic ring 10, having a rounded protuberance or rib 11 on its inner surface. This ring also has a flange 12 to engage the edge of an opening in the container or casing 13 which encloses a condenser or some other electric appliance. The mica discs 4 and 5 rest upon the edges or opposite ends of the ring or sleeve 10; being firmly secured thereupon by the circular clamping means or rings 14 and 15 which are provided with suitable apertures for the retaining screws 16 and 17. The rings 14 and 15 also have rounded edges, like the nuts 6 and 7, to reduce the danger of discharge between the nuts and the clamping rings.

In Figure 3, the electrostatic field existing between the rod 1 and the internal surface of the surrounding tubular support 10 for the mica discs 4 and 5 is diagrammatically represented. The direction of the dielectric lines is thus parallel to the surfaces of the insulating flat mica discs 4 and 5. By such disposition of the insulating material, insulation losses due to the rapidly varying high frequency electric field are greatly diminished and heating effects become much less pronounced.

On the inside of the sleeve or cylinder 10, the space between the rounded rib 11 and the central rod 1 separated therefrom is provided as a sparking or safety gap. The function

of this gap is of course to protect the electrical device to which the terminal is attached in the casing 13 from the effects of excessive voltages. To the end of the rod 1, any suitable electric connection to the apparatus within the casing 13 may be made in any well known manner.

I do not wish to be limited to the precise details of structure shown herein, as changes 10 may readily be made without departing from the spirit or scope of my invention. For instance, it is often advantageous for purposes of ventilation, to supply the upper disc 5 with a few perforations and thus lessen the 15 tendency for the air in the space between the two mica discs to become ionized and thus become conductive between the electrode 1 and hollow support or sleeve 10. The discs or diaphragms 4 and 5 may be made up of several 20 thin sheets or layers of mica, as will be understood.

It is well known that any sharp edge will be the cause of a brush discharge and consequent sparking at a voltage lower than a 25 rounded edge. By rounding off the edges of the metallic ring 10 and the rings 14 and 15, together with the shoulders 3 of the sleeve 2, the safety gap is confined to the space between the rib 11 and sleeve 2 and sparking at any 30 other point is prevented.

Having described my invention, what I believe to be new and desire to secure and protect by Letters Patent of the United States is:—

25 1. A terminal comprising a hollow conductive support, a conductor in the support, and an insulating diaphragm carried by the support through which the conductor passes, the conductor and the support being shaped to 40 provide a safety spark gap between them, and means for completing an enclosure for said spark gap.

2. A terminal comprising a hollow conductive support, a conductor in the support, and 45 an insulating diaphragm carried by the support through which the conductor passes, the conductor and the support being shaped to provide a safety spark gap between them, said support having an internal rib forming 50 one side of said gap, and means comprising a diaphragm for completing an enclosure for said spark gap.

3. A terminal comprising a hollow conductive support, a conductor in the support and 55 an insulating diaphragm carried by the support through which the conductor passes, the support having an external flange to enable the terminal to be mounted, the support and conductor being shaped to provide a safety 60 spark gap between them, and insulating means for completing an enclosure for the said spark gap.

4. A terminal comprising a hollow conductive support, a conductor in the support, and 65 a pair of insulating diaphragms carried by

the support, said diaphragms secured against the opposite ends of the support, the conductor passing through the diaphragms.

5. A terminal comprising a hollow conductive support, a conductor in the support, and a pair of insulating diaphragms carried by the support the conductor passing through said diaphragms, the terminal having an internal safety spark gap between the diaphragms.

6. A terminal comprising a hollow support, a conductor in the support, insulating diaphragms attached to the two ends of the support, said terminal carrying means for clamping the diaphragms to the support, the support having an internal rounded rib, providing a spark gap between the conductor and rib, said terminal having no well defined edges adjacent said rib.

7. A terminal comprising a hollow support, a conductor within the support, an insulating diaphragm carried by the support through which the conductor passes, and an insulating member surrounding the conductor and adjacent to the diaphragm, the support and conductor forming a protective spark gap enclosed by said insulating diaphragm and member.

8. A terminal comprising a hollow support, a conductor within the support, a metallic sleeve in the support around the conductor, a plurality of insulating diaphragms through which the conductor passes, the diaphragms being clamped to said support and against the sleeve, and a plurality of insulating sleeves around the conductor and adjacent to the insulating diaphragms.

9. A terminal comprising a hollow conductive support, a conductor in the support, an insulating diaphragm carried by the support through which the conductor passes, the support having an internal rounded rib to provide a safety spark gap between the same and the conductor, said terminal having no well defined edges adjacent said rib, and an additional diaphragm completing an enclosure for the said spark gap.

In testimony whereof I affix my signature.
ALEXANDER NYMAN.
